UNITED STATES PATENT OFFICE

GEORGE W. SLOCOMB, OF LOS ANGELES, CALIFORNIA

TURBINE PUMP

Application filed March 19, 1928. Serial No. 262,796.

This invention relates to a pump for lifting liquids, such as water and the like, and the principal object thereof is to provide a simple and efficient means for lifting liquids with a minimum amount of power and a greatly reduced amount of friction. To that end I provide a turbine pump having a cylinder in which there are stationary spiral blades arranged a short distance below the water level with a rotor therein including helical blades coiled reversely to the spiral blades; and with the blades so arranged that their adjacent edges are out of contact and so that the rotation of the helical blades will cause the water or other liquid to flow upward on the spiral blades.

In other words I drive the rotor to develop centrifugal force that will cause the water to circulate at high speed around the inner wall of the cylinder so that the spiral blades will act on the whirling water and cause it to flow upward. The centrifugal force is developed by a minimum amount of power; and friction is greatly reduced as the spiral and helical blades are out of contact and the bearings for the rotor shaft are efficiently lubricated and the lower bearing of the rotor floats in the liquid being pumped.

Another object of the invention is to provide a simple means for obtaining high efficiency in liquid pumping by avoiding the back flow of water that is common to many pumps due to such causes as lost or interrupted motion as well as leakage. This is effected by establishing a relatively constant centrifugal force that prevents a back flow or leakage while the pump is in action.

Another object of the invention is to provide a pump with one or more turbine units that can be connected and operated together on a single shaft.

Another feature of invention is shown in the means for supporting and lubricating the drive shaft.

Another feature of invention is shown in the novel means employed for interrupting excessive rotation of the lubricant in the pump head.

Features of invention are shown in the construction, combination and arrangement

of parts whereby a pump is provided that is easy to construct, assemble, install and operate, that is neat and pleasing in appearance and effective and durable in use.

Other objects, advantages and features of invention may appear from the accompanying drawings, the subjoined detailed description and the appended claims.

The accompanying drawings illustrate the invention:

Figure 1 is a fragmental perspective view of a turbine pump constructed in accordance with this invention. Fig. 2 is an enlarged fragmental central vertical section through the pump head showing a detail of the means for driving the turbine shaft and also the means for lubricating the shaft and bearings. Fig. 3 is a cross section on the line 3—3, Fig. 2, showing the fingers for arresting the rotation of the lubricant in the pump head chamber. Fig. 4 is a cross section on the line 4—4, Fig. 5, looking down on the stationary cage, parts omitted for the sake of clearness. Fig. 5 is a fragmental central vertical section on the line 5—5 of Fig. 1 showing three turbine units arranged one above the other, all of which are driven by a single shaft, the lower unit being shown in full section and the upper ones in part section. Fig. 6 is an enlarged fragmentary vertical section through the upper turbine unit with the helical blades and a portion of the shaft broken away to more clearly show the spiral blades that are integral with the inner wall of the cylinder, also showing a bearing connection between the hub of the rotor and the stationary cage. Fig. 7 is a cross section on line 7—7, Fig. 6, with parts omitted for the sake of clearness, showing the spiral blades as arranged on the inner wall of the cylinder. Fig. 8 is a plan view of the turbine rotor. Fig. 9 is a view of the turbine rotor transverse to that shown in Fig. 8. Fig. 10 is a side view of the well cage detached from the pump.

The pump includes a base 12 that can be mounted on and secured to a platform not shown but well understood in the art.

The pump head 13 includes a shell 14 secured to the base 12 by the bolts 15. The base

12 is provided with an annular extension 16 that is tightly fitted in the lower end of the bore through the shell 14 to form a seat for the outer ring of a thrust ball bearing 17.

5 The base plate 12 is also provided with a center bore 18 through which a casing 19 is extended, supported and drawn taut and rigid by a nut 20 arranged in a recess 21. A packing 22 is arranged in an annular recess 10 around the casing and between the nut and base to prevent leakage of lubricant from the chamber 23 in the shell 14 into the water chamber 24 directly below the base 12.

The chamber 24 is formed of a large cylinder 25 secured to the base that has its lower end partly closed by the reducing coupling 26 to which the upper end of the main pump cylinder 27 is secured.

15 A discharge pipe 28 is brazed to or otherwise secured to the cylinder 25 so that water can pass from the chamber 24 when necessary.

Another ball bearing 29 is secured in the shell 14 and spaced from the bearing 17 by a spacing sleeve 30 that is secured on a bearing sleeve 31 that carries the inside rings of the bearings 17 and 29. The sleeve 31 has its upper end secured to the hub 32 that is secured on the upper end of the shaft 33 by a key 134.

30 The hub 32 has an annular flange 34 that is secured to another hub 35 on a pulley 36 by pins 37. The hub 35 is formed with an internal hollow flange 38 that is fitted snugly over the upper end of the sleeve 31 and has its lower end resting on the internal ring of the bearing 29. Also this hub has an external flange 39 that is secured to the inner wall of the pulley 36.

The upper end of the shell 14 is threaded 40 for a hollow plug 40 that has spaced fingers 41 extending downward into the chamber 23 to arrest or interrupt rotation of the lubricant in the upper end of the chamber so that it will not climb out over the end of the shell 14 and be wasted.

45 The chamber 23 can be filled with lubricant through the stand pipe 42 that is connected to the passage 43 in the base 12 by a connection 44 that is provided with a drain plug 56 144. The pipe 42 is provided with a screw cap 45 that is removable for charging the chamber and also the pipe is provided with a sight glass 46 so that an operator can see when the proper amount of lubricant has been supplied to the chamber.

An oil passage 47 is provided in the upper end of the shaft 33 that is normally closed by a plug 48 that can be removed for introducing oil through the passage 47 to the shaft bearings.

55 The shaft 33 has its upper end threaded for the nut 49 which is utilized to slightly raise or lower the shaft when necessary, the purpose of which will be explained later.

5 The hollow plug 40 can be slightly raised

and lowered by means of an extension 49 that can be engaged by a tool extending through one of the holes in the extension 34 when a pin 37 is removed. That is a tool is inserted through the pin hole to engage one side or the other of the extension 49. Then by turning the pulley 36 in one direction or the other the plug 40 can be raised or lowered as desired.

The shaft 33 is provided with a socket in its lower end in which the upper end of the shaft 50 is secured. The shaft 50 is considerably reduced in diameter, as is also the casing 51 that surrounds it. In other words the casing 19 is connected to the casing 51 by a reducing coupling 52; and adjacent the coupling a bushing 53 is arranged around the shaft 50.

There is a clearance 54 between the shaft 50 and the casing 51 which at the bottom end 85 of the casting is filled by packing 55 supported on a plug 56, see Figs. 5 and 6. The lower end of the casing 51 is externally threaded and secured in the center bore 57 through a spider 158 in the cage 58 that is secured to the lower end of the cylinder 27.

It is understood that the cylinder 27, shaft 50 and casing 51 are of sufficient length to reach as much below the water level indicated by the line a—a in Fig. 6 as may be desired; 95 and when of great length these parts are formed in sections and coupled together in the usual way.

The cage 58 is externally threaded at 59 to which the upper end of the first turbine unit 100 or cylinder 60 is secured.

The cylinders 60, 61 and 62 are constructed substantially alike except in the connection of the unit 62 with the inlet strainer 163 so that a description of one will describe all of them. 105

It is understood that I may employ a single unit if so desired or that I may add as many more of the turbine units as are necessary.

Integral with the inner wall of the turbine 110 cylinder 60 are spaced spiral blades 63 that preferably are tapered from their upper ends outwardly and downwardly, and a rotor, including helical blades 64 that are coiled reversely to the spiral blades, is arranged to be 115 revolved centrally in the cylinder 60.

The blades 64 have their upper ends connected to a flange 65 on a hub 66 secured to the shaft 50 by pins 67. The hub 66 of the upper rotor is arranged to rotate in the lower end of the bore 57 in the spider 158 and preferably there is an annular bearing ring 68 extended upward on the flange 65 of this hub that enters an annular socket 69 in the spider; and the purpose of this annular extension and socket is to form a bearing for the shaft as well as to prevent leakage of the agitated water into the space around the shaft above the packing 55.

In the event that water escapes over the 120

bearing ring 68 toward the shaft 50 it will be thrown out of the recess 70 through the outwardly and downwardly inclined holes 71 when the pump is in action, see Fig. 6.

5 The helical blades 64 have their lower ends connected to a bearing ring 72 that is arranged to rotate in an annular socket 73 that is formed by a fitting 74 secured to the upper ends of the lower and intermediate cylinders 61, 62, which fitting has annular flanges 10 75 that are spaced inwardly a sufficient distance to form a clearance or socket between their outer walls and inner walls of the cylinder for the bearing rings 72 to enter and rotate to stabilize the rotor.

15 The fitting 74 in the lower end of the cylinder 62 is slightly different in form from the other fittings and it is provided with an internal thread for the upper end of the strainer 163; otherwise it functions substantially as do the other fittings.

20 The fittings 74 are first used as a support in assembling the various rotating parts of the pump. In other words as the parts are assembled the rings 72 extend into the slots 25 so as to support the other parts being assembled, after which the rings 72 are slightly elevated by tightening the nut referred to heretofore.

25 Also when the nut 20 is tightened all the slack between the pump head and cage will be taken up; and the casing that holds the bearings for the shaft is held tight and rigid. When the nut 49 is tightened the shaft 50 and 30 its rotors will be slightly elevated so that there is a slight clearance between the bottoms of the rings 72 and sockets 73.

35 The upper ends of the rings 72 are tapered from their inner edges upward and outward so that when in use centrifugal force will deflect sand and the like upwardly so it will not likely pass into the bearings around the rings. The clearance between the rings 72 and the walls of the annular sockets 73 is 40 very slight but sufficient to form both an inner and outer jacket of water for the rings so that in use they practically operate in a water lubrication and never are in exact frictional contact with the walls of the sockets. However the bearings for the rings 72 are sufficient 45 to prevent excessive vibration when the shaft 50 is driven at high speed.

50 Preferably the spiral blades 63 and helical blades 64 are arranged so that there never is contact between their adjacent edges, but they are very close together and as previously stated they are reversely coiled so that when the shaft 50 is driven the water rotated by the helical blades will be forced upward on the spiral blades.

55 60 When the water has been driven upward past the uppermost spiral blades it is driven into the cage 58 which is provided with spaced deflectors 76 that act to deflect the water from a rotary to a vertical course.

65 The deflectors 76 at their lower ends are

provided with curved points 77 that are adapted to coact with the vertical deflectors 76 to change the course of the water as best indicated in Figs. 4 and 10.

In operation the parts are assembled as described and the shaft 50 rotated to drive the rotors so that they will force water upward on the spiral blades, through the cage and out of the discharge pipe 28.

I claim as my invention:

1. A turbine pump including a stationary vertical cylinder, spiral blades secured to the inner wall of said cylinder and encircling a rotor, said rotor comprised of a hub with helical blades curved reversely to the spiral blades and extending downwardly from and connected to the lower part of the hub by their upper ends only and supported centrally in said cylinder, a ring secured to and surrounding the lower parts of the rotor blades, said ring fitting closely but loosely in said cylinder and adapted to rotate immediately below the spiral blades to stabilize rotation, and means for supporting and rotating said rotor.

2. A turbine pump including a stationary vertical cylinder, spaced spiral blades integral with the inner wall of said cylinder, a shaft arranged centrally in said cylinder, a hub secured to said shaft, helical blades curved reversely to said spiral blades and having their upper ends integral with said hub and arranged with their outer edges adjacent to but out of contact with the inner edges of said spiral blades so that they force the liquid outwardly between and upwardly on said spiral blades, a ring integral with the lower ends of said helical blades, an annular bearing secured to the inner wall of said cylinder below said spiral blades into which said ring is extended and adapted to rotate, and means for rotating said shaft.

3. A turbine pump including a cylinder held from rotation, spiral blades integral with the inner wall of said cylinder, said blades arranged to taper outwardly and downwardly, a shaft supported centrally in said cylinder, a hub on said shaft, helical blades on said hub that are curved reversely to said spiral blades and which taper inwardly and upwardly and which have their outer edges adjacent to but out of contact with the inner edges of said spiral blades and which are arranged to force the liquid outwardly between and upwardly on said spiral blades, an annular ring integral with the lower ends of said helical blades, and an annular bearing in which the lower portion of said ring is mounted and adapted to rotate.

4. In a turbine pump the combination of a plurality of liquid lifting units each including stationary spiral blades and rotary helical blades reversely coiled, a bearing below each of said units for stabilizing the helical blades, a cage above said units, and

means for rotating said helical blades so that liquid will be forced outwardly between and upwardly on said spiral blades through said cage.

5. In a turbine pump the combination of a cylinder having spiral blades secured to the inner wall thereof, a cage in said cylinder with an annular socket in the bottom thereof, a shaft extending through said cage, a hub on said shaft, a flange on said hub that has passages therethrough that are inclined downwardly and outwardly from the vertical axis of said shaft, an annular bearing extension on said flange extending into the socket in said cage, and helical blades secured to said flange for the purpose specified.

6. In a turbine pump the combination of a head including a stationary shell having an oil chamber therein, an adjustable plug at 20 the upper end of said shell, fingers attached to said plug that extend downwardly into the oil chamber to interrupt rotation of oil around the inner wall of said shell, a shaft extended through the chamber, and means 25 connected with said head and shaft for pumping water.

In witness whereof, I have hereunto affixed my signature.

GEORGE W. SLOCOMB.
